UNITED STATES PATENT OFFICE.

GEORGE MCKIBBIN, OF NEW YORK, N. Y.

PAPER-CLIP.

SPECIFICATION forming part of Letters Patent No. 355,943, dated January 11, 1887.

Application filed October 1, 1886. Serial No. 215,054. (No model.)

To all whom it may concern:

Be it known that I, GEORGE MCKIBBIN, of New York, in the county and State of New York, have invented a new and useful Paper-Clip, of which the following is a specification.

My invention relates to means for holding or fastening sheets of paper together, and to a suitable support backing or tablet, so that the sheets shall be held firmly and smooth when being written upon or examined, but can be readily detached when filled with writing, or for use apart from the fastening.

More specifically, my invention relates to a clip or fastener or binder for packets or pads of writing or memorandum paper and the like, in which the sheets are fastened together on the edges, and the packet of sheets thus held fastened to a back forming a tablet. In such case, when one side of a sheet is written upon and it is desired to use the other side, before turning the sheet it must be torn or separated from the packet, and when turned there is no way provided for again fastening it. The clip or fastener can also be applied to a board of any kind to bind loose papers to a suitable back or tablet.

The object of my invention is to make paper clips or fasteners separate from the tablet or board to which they are designed to be attached, and adapt them to be transferred from one board or tablet to another.

A further object of the invention is to adapt the clip to fasten itself to the board or tablet.

In the accompanying drawings, Figure 1 represents a perspective view of my improved paper fastener or clip applied to a packet of paper; Fig. 2, a plan of the fastener detached; Fig. 3, an end view on an enlarged scale.

Referring to the drawings, A represents the packet of paper, consisting of any practicable number of sheets, laid upon a board or tablet, a, and which may be secured thereto by pasting a strip of paper (represented by dotted lines, Fig. 1) to the back of the board and against the edges of the paper on its longer side and one end or edge, or against one edge only, if preferred. This is what is ordinarily known as a "memorandum-pad."

The clip or fastener consists of two parts—viz., the part which connects with the board or back of the pad and forms the clasp B, and the part which fastens the sheets and forms

the clamp D. The clasp consists of a plate of metal or other suitable material, of the proper length, folded lengthwise, so that the bottom 55 b and top b' meet at their front edges, and together form a spring-clasp, between which is inserted an end of the back or tablet, where it is held and clasped firmly. In the ends of the bottom plate, b, suitable cuts are made and 60 the metal thrown up so as to form stops d d. The top plate is also cut at the ends to permit parts thereof to be turned up at right angles and form stops e e.

The clamp or clip D consists in this instance 65 of a screw-threaded stud or post, f, placed midway of the clasp D in a vertical position and in line with stops d d, and is fastened by riveting its inserted end, which is passed through the bottom plate, against the underside of said 70 plate, and of a clamping-piece, g, having a shank 1 provided with a screw-threaded hole for the stud f. The clamping-piece is convex on its under side, which presses upon the top sheet of the pad. The purpose in so making 75 it is to prevent its catching in the edges of the packets when turned around to rest and press upon the paper. As this clamp is adjusted to bear upon the paper with the proper force by screwing it up or down, if it were perfectly 80 flat it would be liable, if screwed the slightest distance too far down, to catch or strike the edge of the top sheet and pass under the same; but by making it convex, without any nicety of adjustment, it passes without difficulty over 85 the edge of the paper, and also can be made to press with force upon the paper without screwing it directly down upon the same. The clamp may, however, be made to act in a different manner—as, for example, it may be 90 controlled by a spring, or it may be formed into a cam, or otherwise made differently from the one shown and described; and in such case the shape will be adapted to the manner in which it operates to clamp the paper.

95 The device is used in the following manner: The clamp being raised to the proper position to admit the packet of paper under it, the end of the board or tablet where the sheets are free is thrust into the clasp and pushed back until 100 it comes in contact with the stops. In the case of the pad, when the edges of the paper on one side are pasted together and to the board, the end of the pad comes in contact

with the stops *e e*, and the top plate, *b'*, passes under the pad, or between it and the board; but where loose papers are to be fastened by the clamp, the board is thrust in until it is stopped by the stops *d* and the screw-stud, and the papers are laid upon the board or tablet and fastened by the clamp alone. It is in this case that the stops *d* become of use, as if the screw-stud *f* were alone depended upon as a stop the board would be liable to turn upon it sidewise as a center, and it would not be kept square with the clasp.

Owing to the ease with which the papers can be clamped and unclamped when a sheet is filled, the clamp can be turned aside, the sheet torn off, laid with its clean side up on the packet, and the clamp turned back upon it, whereby it is securely held on the packet.

I do not limit myself to the use of a clasp for connecting the clip with the board, as other means offering facilities for a quick and simple attachment may be substituted for it.

I claim—

1. In a paper-clip, the combination of a plate formed into a spring-clasp with an adjustable clamp, substantially as and for the purpose specified. 25

2. The stops *d d*, in combination with the clasp and a suitable clamp, substantially as specified. 30

3. The combination of the clasp, the stops *e e*, and a suitable clamp, substantially as specified.

4. The adjustable convex clamping-piece *g*, in combination with the clasp of a paper-clip, substantially as specified. 35

5. As a new article of manufacture, a paper-clip composed of the clasp *B*, for connecting with the board or tablet on which the paper is placed, and having the stops *d d* and *e e*, and the clamp composed of the screw-stud *f* and clamping piece *g*, substantially as specified. 40

GEORGE MCKIBBIN.
